ABSTRACT: This invention relates to an improved method and apparatus for piecing-up broken yarn ends in a spinning frame of the type including fiber drafting means, twisting spindles, and a vertically reciprocable ring rail.

The apparatus comprises a carriage mounted on the spinning frame for movement therealong and carrying a supply of auxiliary yarn. The carriage has a portion movable up and down with the ring rail and carrying means for operatively engaging the free end of the auxiliary yarn with a ring traveller and also with a bobbin on the spindle for winding and twisting the yarn. The carriage also carries means for moving an intermediate portion of said yarn into engagement with a broken yarn end or roving extending from the front drafting rolls into a flute, so that when the auxiliary yarn is severed adjacent the roving it will untwist and attach itself thereto to effect the piecing-up operation. In the preferred embodiment the carriage has means for automatically withdrawing a predetermined length of auxiliary yarn and storing it for subsequent release into a narrow passage where it is held under tension just prior to a piecing-up operation.

YARN PIECING APPARATUS FOR SPINNING FRAME

BACKGROUND OF THE INVENTION

In the general type of known and conventional yarn piecing-up devices and their methods it is customary that a fibrous strand or roving is pieced up together with a yarn or thread by contacting the yarn with a roving which is held against a roller of the machine while the broken roving is being sucked into a flute and the yarn is being twisted. But in such a system the corresponding roving to be contacted with the strand is traversing upon the bottom front roller in an axial direction relative to the roller between both ends thereof so that, except for the case where its position is opposite that of the yarn to be approached, but, for example, in the case that the roving is at a position where its traverse has been completed, there is a considerable distance between the yarn and the roving in the axial direction relative to the roller. Viewed from the direction of the bottom front roller axis, at the upper and lower side of the nip point between the bottom front roller and a member engageable with this bottom front roller and by which the yarn is pressed toward the roving as the latter and the yarn are separated from each other gradually proportional to the distance from the nip point, it is almost impossible to perform a reliable piecing-up of both of them, when at the nip point the roving and the yarn are separated in the direction axially of the roller. Consequently, it had not been considered that a fully automatic yarn piecing-up device and method in combination with a yarn breakage detector would be possible until disclosure of this concept was made.

SUMMARY OF THE INVENTION

This invention is to provide for a yarn piecing-up device and method for spinning frames with which, even if the roving is positioned at any position of transverse range, a reliable yarn piecing-up can be conducted easily, and is intended for simplification of a full automation of yarn piecing.

A piecing-up device and method for spinning frames to piece to a roving a free end of the yarn to be pieced while the latter is being twisted and pulled by means capable of pulling the yarn while twisting it, said device and method comprising means as follows:

a. means for holding the yarn being twisted while being pulled at one end thereof by said twisting and pulling means while at the same time preventing said yarn from being too quickly pulled into said twisting and pulling means, said holding means serving to store turns of twist in the body of the yarn between the holding means and the twisting and pulling means by the utilization of the twisting action of the twisting and pulling means;

b. means for forcibly advancing an intermediate portion of said yarn to an area medially of the roving, said advancing means including an element adapted to contact the medial portion of said yarn between said twisting and pulling means and said holding means and move it toward the roving so as to approach the medial portion of the roving, said advancing means serving to forcibly move that intermediate portion of said yarn which is on that side of the place of contact between the yarn and said element where said holding means is positioned to that intermediate portion of the roving which is moving in a free space in a direction substantially the same as the direction in which said yarn is being pulled;

c. means for severing that portion of said yarn which is on the side of the place of its contact with said element where said holding means is positioned so as to allow said yarn portion to assume a state having a free end after the intermediate portion of said yarn and the medial portion of the roving have been brought into either closely adjacent or contacted relation to each other by said advancing means; and

d. means for restoring said means (a), (b), and (c) to their original positions.

Thus, there is provided a means for contacting or approaching a roving portion, moving in front of the bottom

front roller of a draft frame, with an auxiliary yarn by shortening the axial distance on said bottom front roller with respect to said auxiliary yarn to be approached by a yarn approaching means, in general, even if there is at any position on said bottom front roller said roving traversing by a traverser in the roller axial direction under said bottom front roller, it is possible to reliably intertwine said roving with said auxiliary yarn and to piece each other only by moving said auxiliary yarn being twisted and wound on a bobbin under said bottom front roller surface by said yarn moving means.

According to this invention, while it is easy to fix an axial position of said auxiliary yarn to be contacted with said roving under said bottom front roller, and said roving is changing its position in the axial direction of said bottom front roller axis every moment within its traversing range even if said roving is at either extreme end of its traverse, it is possible to contact said roving with said auxiliary yarn as it approaches said bottom front roller and to piece them together. Moreover, the time of approach toward said bottom front roller for piecing said auxiliary yarn is not fixed. If roving breakage happens, yarn piecing operation begins immediately, therefore an efficient piecing can be conducted. In the event that a full automatic yarn piecing is to be carried out, the yarn piecing-up device may be arranged in parallel along the row of spindles and if a roving breaks, the yarn piecing-up operation may be begun at once. As it is unnecessary for an operator to use any means for detecting the position of breakage of said roving in the direction of said bottom front roller axis and adjusting the position of said auxiliary yarn to be pieced in accordance with that of said roving, a reliable automatic yarn piecing can be performed efficiently.

In a preferable embodiment according to this invention, there is shown a piecing-up device for spinning frames including a means for advancing said auxiliary yarn toward said roving comprising a solid guide element which contacts with said roving under motion in a free space.

The present inventors have learned that a roving moving in a free space which if broken is to be sucked into the flute of a pneumatic clearer from said bottom front roller, permits spreading at least in one part of its fibers by being contacted with a suitable element from a lateral direction with respect to that of its movement. Consequently, they now also know that, if this feature is used, and a yarn to be pieced is previously positioned at the contacting surface or adjacent to that of said roving on said element, that is, the solid guide element, and contacting at least one part of the fibers of said roving with said auxiliary yarn, they can be intertwined with each other easily by the untwisting of said auxiliary yarn.

In other words, in the case that said roving is moved adjacent to said auxiliary yarn to be pieced, if a method for positively moving said roving is used, its mechanism will not only be intricate, but also, when the roving which gets broken easily is advanced in such a manner as this, the roving is apt to be broken during the advancing process. In the instance of contacting said guide element with said roving as mentioned above, its construction becomes not only simple, but also one section of said roving spreads itself and can be contacted with each other by approaching said auxiliary yarn to be pieced so one can perform a reliable yarn piecing-up in such a state as that before both said auxiliary yarn to be pieced and said roving are pieced to each other, said roving may not be broken.

In a particularly preferable embodiment, the guide element comprises a notched plate member communicating with an aperture, said plate being resilient and displaceable in a lateral direction relative to the travel of the roving with the joining of the yarn with the roving taking place in an area adjacent to the notched plate and the aperture in the notched plate being too narrow to permit entry of the roving.

When such construction is adopted, with the auxiliary yarn to be pieced with the roving travelling through said aperture, said roving at the same time may pass perpendicularly relative to the plate member whereby it will be spread open. Immediately thereafter said yarn while under tension and twisted

is severed between the braking means and the drafting means whereby the severed portion untwists and becomes united with the roving.

An object of the invention is to devise an apparatus and a method capable of causing the fibrous strand or roving extending from the drafting means to be swollen to such an extent that it will be more intimately engaged with the twisted auxiliary yarn after it is severed and begins to untwist about its axis.

A further object of the invention is to provide an automated method of piecing-up broken ends on a spinning frame of the type including fiber drafting means and a twisting spindle.

Further objects and advantages of the invention will become apparent after a careful reading of the following detailed specification taken in conjunction with the drawings.

The term "yarn" is to be understood to be generic to textile strands, such as yarns, threads and filaments and the term "fibrous strand" is to be considered generic to slivers and rovings.

BRIEF DESCRIPTION OF THE DRAWINGS

FIG. 1 is a front elevational view showing the first embodiment of the invention;

FIG. 2 is a side elevational view of the structure of FIG. 1 partially in elevation and partially in cross section with the upper part of the elements shown enlarged;

FIGS. 3 and 4 are detailed side elevational views partially in cross section and partially in elevation showing certain elements in different position of operation;

FIG. 5 is a detailed, enlarged, side elevational view partially in cross section showing an ancillary unit for supplying the yarn to a traveller;

FIG. 6 is a perspective view showing a mechanism for piecing the broken end of the yarn and the auxiliary yarn together;

FIG. 7 is a side view of the elements shown in FIG. 6;

FIG. 8 is a top plan view of the same elements;

FIG. 9 is a cross-sectional view taken along line 9-9 of FIG. 8; FIG. 10 is a cross-sectional view taken along line 10-10 of FIG. 7;

FIGS. 11 and 12 are side and top plan views, respectively, showing the manner in which the auxiliary yarn is being supplied to the traveller;

FIG. 13 is a side elevational view partially in section showing the second embodiment of this invention;

FIG. 14 is a side elevational view in partially enlarged detail showing the auxiliary yarn supplier and the mechanism for piecing the roving and the auxiliary yarn;

FIG. 15 is a top plan view of the elements of FIG. 14;

FIG. 16 is a top plan view showing in detail the principal element of FIG. 14;

FIG. 17 is a cross-sectional view taken along line 17-17 of FIG. 16;

FIG. 18 is a side elevational view in enlarged detail partially showing an auxiliary yarn supplying element for the traveller;

FIG. 19 is a top plan view of FIG. 18;

FIG. 20 is a cross-sectional view taken along line 20-20 of FIG. 19;

FIG. 21 is a cross-sectional view taken along line 21-21 of FIG. 20;

FIGS. 22-32 are the outline views in perspective showing each step in the process in accordance with which the auxiliary yarn supplier moves toward the traveller;

FIG. 33 is an enlarged side elevational view showing elements in the lower half of FIG. 13;

FIG. 34 is a front elevational view of the elements of FIG. 33;

FIGS. 35A and 35B are the timing graphs of a spinner;

FIG. 36 is a side elevational view partially in section showing the condition of the yarn-piecing system prior to its commencement of the yarn-piecing operation as taught by the third embodiment of the invention;

FIG. 37 is a side elevational view partially in section showing the condition of the yarn-piecing system as operation begins;

FIG. 38 is a side elevational view partially in section showing the condition of the auxiliary yarn which has been cut;

FIG. 39 is a perspective view showing a suction nozzle;

FIG. 40 is a surface top plan view of FIG. 36;

FIG. 41 is a side view partially in elevation and cross section showing the condition wherein a fixed length of yarn is

10 spooled according to the fourth embodiment of the invention;

FIG. 42 is a view similar to FIG. 41 partially showing the condition where the spooled yarn has been rapidly supplied;

FIG. 43 is illustrative of a position where the intermediate portion of the auxiliary yarn is wound on a bobbin according to the fifth embodiment of the invention;

FIGS. 44 and 45 are front elevational views showing the principal element of the fifth embodiment;

FIG. 46 is a vertical sectional view taken along line 46-46 of FIG. 45; and

FIGS. 47 and 48 are frontal views showing the principal elements of a further modified embodiment of the present invention.

FIRST EMBODIMENT OF INVENTION SHOWN IN FIGS. 1-12

An apparatus for joining ends of yarn of this example consists of the following:

- A. A carriage and a device for fixing a location thereof.
- B. A broken yarn joining device.
- C. A supplementary device for supplying an auxiliary yarn to a traveller.

The above-mentioned devices will be described in due course.

A. A Carriage and a Device for Fixing a Location Thereof

As shown in FIGS. 1 and 2, spindle rail 15 has an upper rail 16 and a lower rail 17. Wheels 19-19 with flanges are journaled at the upper portion of a carriage 18, said wheels riding on the upper rail 16. Also, rollers 20-20 are journaled on vertical axes at the lower portion of the carriage 18, said rollers 20-20 laterally engaging the lower rail 17. Thus, the carriage 18 is able to move freely along the spindle rail 15. The carriage 18 also has a movable arm 23 at the lower portion thereof and by the side of the spindle rail 15, said movable arm 23 being supported pivotally at 22 on a bearing plate 21. Said movable arm 23 has a bifurcated spindle holder 24 extending from the upper portion thereof toward the spindle rail 15, and also has an actuating arm 28 which projects through an aperture or window 27 in the carriage 18. Said movable arm 23 is biased by means of a torsion spring 26 located on the pivot 22 in a direction away from rail 16 in order to prevent holder 24 from engaging a spindle 25. Also, an operating plate 29 pivotally supported at 30 on the lower outside portion of the carriage 18 cooperates with the free end of the actuating arm 28 to move arm 23 toward rail 15 against the bias of spring 26.

B. A Broken Yarn Joining Device

As shown in FIG. 2, a C-shaped arm 32 is pivotally supported at 31 at an upper portion of said carriage 18; and as shown in FIG. 3, the outward turning motion of said arm 32 from its normal position is limited by means of an arm receiver 33 which extends from the carriage 18. Near the fulcrum 31 of the C-shaped arm 32 is provided with a projection or catch means 34 which is engaged by a latch 35 pivoted at 36 to the arm receiver 33 in order to prevent the C-shaped arm 32 from turning inwardly. A spring 37 biases the latch 35 towards the engaging position, and allows the latch 35 to operate automatically when the arm 32 returns from the inner position of FIG. 4. A movable body 39 is so held at the outside of the carriage 18 by means of guides 38-38 as to be freely movable up and down. Said movable body 39 is so positioned that its lower nose portion 40 will engage the upper arcuate face 41 of arm

28. Near the upper portion of the movable body 39 is provided a projection 42 which extends toward said latch 35 and acts counter to the influence of the spring 37 (FIG. 4). Between the movable body 39 and one of the guides 38-38 is provided a spring 43 which biases body 39 downwardly. A detent or latch portion is provided at the free end of arm 28 and in which the lower nose portion 40 of the movable body 39 is adapted to be engaged. When the bifurcated spindle holder 24 moves upwardly and grips the spindle 25 to hold the movement of the carriage 18 in check, the spring 43 will move body 39 downwardly to engage nose portion 40 with the latch portion 44 (FIG. 14). At the same time, projection 42 causes the latch 35 to release catch 34 thus permitting the C-shaped arm 32 to turn inwardly. However, the lower nose portion 40 of the movable body 39 being engaged in the detent portion 44, prevents the spindle holder 24 from moving under the action of the spring 26. Said movable body 39 is provided with an arcuately formed slotted portion 45 at its upper extent. A pin 46 carried by the C-shaped arm 32 projects therefrom and loosely fits in the aperture 45. These elements operate as follows: when the movable body 39 is in its lowest position, as best shown in FIG. 4, the C-shaped arm 32 turns inwardly, the pin 46 in cooperation with the aperture raises the movable body 39 a little and disengages its lower portion from the detent portion 44 at which time the movable arm 23 is moved outwardly by means of the spring 26. As shown in FIG. 2, the upper extremity of the C-shaped arm 32 is provided with a device 51 comprising a fixing body 47, an auxiliary yarn gripper 48, a yarn joining roller 49 and a guide 50. As shown in FIGS. 6-9, said auxiliary yarn gripper 48 comprises a fixed member 53 secured to a supporting plate 52, a movable member 55 pivoted at 54 to the supporting plate 52 and a spring 56 which urges the movable member 55 against the fixed member 53. The upper portions of both members 53 and 55 are inclined in a V-shaped manner in order to introduce a yarn therebetween. A guide plate 58 is also secured to said supporting plate 52 adjacent to the auxiliary yarn gripper 48, and is provided with a blade 59 which will cut a yarn that has entered a Y-shaped guide groove 57. Said guide 50 comprises a plate 62 having converging edges which merge into a slot 63. Said plate 62 is supported by a spring arm 61 located within a frame 60 which is capable of swinging in a lateral direction. As shown in FIG. 8, said plate 62 is located under the roller 49 and has a Y-shaped yarn guiding slot 63 at its front edge and which terminates in a yarn guiding hole 64 provided at the innermost part of the yarn guiding slot 63. The C-shaped arm 32 provided with the above-mentioned elements is operated by hand by means of a handle 65, as shown in FIG. 2.

As also shown in FIG. 2, an auxiliary yarn 68 unwound from an auxiliary yarn bobbin 67 supported by a bobbin holder 66 provided at the carriage 18, is guided by a thread-guiding member 69 and, as shown in FIG. 3, by an aperture 71 provided on a support plate 70 which extends from the upper guide 38. The filling yarn is restrained by a resilient braking member 73 positioned between the guiding plate 70. Said braking member 73 is supported by the plate 70 and includes projection or leg 74 which passes upwardly through an aperture provided in the middle portion of the plate 70. When arm 32 is moved to the outer position where it is held by latch 35, the projection of leg 74 is forced downwardly. As the projection 74 is forced downwardly, member 73 is released from braking position as shown in FIG. 3. As shown in FIG. 4, when the C-shaped arm 32 turns, the braking member 73 returns elastically and performs its braking operation at its edge portion.

C. A Supplementary Device to Supply Auxiliary Yarn to a Traveller

As shown in FIGS. 1 and 5, this supplementary device has a slide member 76 arranged to move freely up and down and connected by pairs of guide rollers 75 to the carriage 18. Said slide 76 includes a leg 78 which extends at right angles from

the upper portion thereof and is arranged to engage a ring rail 77. Said slide 76 also supports nozzle 80 which emits a current of air in the same direction as the turning direction of the spindle 25, i.e. toward the inside of the ring 79 and is operative only when the projection 78 is in engagement with the ring rail 77, as shown in FIGS. 5 and 12. The nozzle 80 is connected by a flexible conduit 82 to a blower 81 carried by the carriage 18. Also, the slide 76 has a pivotal latch 84 which is biased to latching position by means of a spring 83. Said latch 84 engages within an apertured portion 85 provided on the carriage 18. When the latch 84 engages within the apertured portion 85, the projection 78 is positioned at a position higher than the highest position to which the ring rail can be raised.

In order to disengage the latch 84 from the apertured portion 85 against the spring 83 an operating lever 86 is connected by a rod 88 to the latch 84. Said operating lever 86 is pivotally supported by a handle 87 in order to be operated together therewith, the latter forming the means to raise and lower the slide 76. The construction of the whole apparatus is as has been described above. Under a lower front roller 90 of a drafting device 89 there is provided a flute 91 of a pneumatic clearer which draws in a broken strand 93 (e.g. a roving), as shown in FIGS. 2, 6 and 9. In FIG. 2 the numeral 92 represents a wire guide eye. In FIGS. 2, 5, 11 and 12, the numeral 94 is a bobbin positioned on the spindle 25. In FIGS. 11 and 12 the numeral 95 is a traveller.

To perform a yarn joining operation, the following takes place. To begin with, the carriage 18 is moved along the rails 16 and 17 in front of a spindle where the yarn is broken. Next, as shown in FIGS. 3 and 4, the operating plate 29 is pushed by hand in turn the movable arm 23 against the spring 26. Then, the bifurcated spindle holder 24 carried by arm 23 is fitted onto the lower extremity of the broken yarn spindle 25, and by so doing the location of the carriage 18 is fixed. At that time, the movable body 39 is forced downwardly by means of spring 43, and its lower portion 40 engages the detent portion 44, and thereby prevents the spindle holder 24 from moving and at the same time the upper projection 42 turns the latch 35 and releases the C-shaped arm 32.

Under these conditions, as shown in FIG. 3, the braking member 73 is not in contact with the bent portion 72 of the plate 70 and is not restraining the auxiliary yarn 68. Therefore, the upper portion of the auxiliary yarn which is held by the gripper 48, as shown in FIG. 2, is drawn out and passed around the outer side of the roller 49 as indicated by the dot-dash line, and then passed through the guide 50, and finally drawn out to the ring 79. Then, the latch 84 is disengaged from the apertured portion by means of the operating lever 86, and the slide 76 is moved downwardly to a level indicated by the dot-dash line in FIG. 5, and the leg 78 is brought into engagement with the ring rail 77 which is moving up and down. Then, the slide 76 and the nozzle 80 are allowed to move synchronously with the ring rail 77. As a result, the stream of air which gushes out of the nozzle 80 circles along the inside of the ring 79, as shown in FIG. 12, and thus, the traveller 95 is caused to turn together with the tangential flow of the stream of air. In such a condition as described, a portion of the auxiliary yarn 68 which is drawn out, as shown in FIG. 11, is allowed to advance along the turning route of the traveller 95, and by so doing the traveller 95 is automatically engaged with the auxiliary yarn 68. If the idle end of the auxiliary yarn 68 is set free, the circling stream of air caused by tangential flow from the nozzle and the turning motion of the bobbin 94 causes the idle end of the auxiliary yarn 68 to be wound on the bobbin 94, as shown in FIG. 12.

The C-shaped arm 32 is turned by handle 65 in FIG. 2. When this arm 32 moves away from the projection or leg 74, as shown in FIG. 4, the braking member 73 stops the auxiliary yarn 68. Thus, the auxiliary yarn 68 is prevented from being drawn out even though the bobbin 94 is turning, and thereby a strong twist is given to the auxiliary yarn 68. It is to be understood that at this time the auxiliary yarn 68 has not yet entered between the fixed member 53 and the movable member

55 of the auxiliary yarn gripper 48 (FIG. 6), and is merely in engagement with the upper portion thereof.

As described above, a strong twist is given to the auxiliary yarn 68. Thus, when it moves on the roller 49 (FIGS. 6 and 9) it travels to one side at the same time swinging the notched plate 62 of the guide 50 laterally against the elasticity of spring arm 61.

When the roller 49 has finally come in contact with the lower front roller 90, as shown in FIG. 9, the roller 49 is driven thereby and the auxiliary yarn 68 is pulled taut. Thus, the auxiliary yarn 68 restrained by the braking member 73 (FIG. 4) pushes the movable member 55 open against the spring 56 and enters between the fixed member 53 and the movable member 55. The auxiliary yarn is guided by the Y-shaped yarn guiding groove 57 of the guiding plate 58 and is pressed against the blade 59 and is thereby cut. On the other hand, the strand or roving 93 which has been already drawn into the flute 91 is pressed against the Y-shaped yarn guiding slot 63 provided at the plate 62 on the guide 50, and is swollen a little in a lateral direction on the plate 62. As a result, a portion of the strand winds itself around the auxiliary yarn 68 which is being twisted taut. When the auxiliary yarn is cut with blade 59, it is no longer taut, and the cut end of the auxiliary yarn untwists. This motion together with the following twisting motion causes the auxiliary yarn 68 and the strand 93 to wind themselves completely around each other, and they are thereby connected. The portion of the strand which has been drawn in the flute 91 at that time is separated from the following portion which has wound itself around the auxiliary yarn 68.

In yarn joining operations as described heretofore, the guide 50 operates very satisfactorily to join the traversing strand 93 and the auxiliary yarn 68 together.

Upon coming into contact with the lower front roller 90, the roller 49 is immediately pulled back. When the roller 49 comes into contact with the lower front roller 90, that is, near the end of the travel of the C-shaped arm 32, the pin 46 raises the movable body 39 and disengages its lower portion 40 from the detent portion 44, as shown in FIG. 4. Thus, the movable arm 23 returns to the position shown in FIG. 3 by means of the spring 26, and its spindle holder 24 is removed from the spindle 25, and the carriage 18 is released.

When the handle 65 shown in FIG. 2 is pulled towards the operator, the roller 49 is moved away from the lower front roller 90. Also, when the guide 50 is moved from the strand 93 and the C-shaped arm 32 is returned to its original location, the projection 34 automatically engages the latch 35. The braking member 73 is also returned to the nonbraking position at that time. As shown in FIG. 2, the auxiliary yarn 68 is gripped at its end portion by the auxiliary yarn gripper 48, thus, the yarn joining operation at the next broken yarn spindle is performed in the same manner as described above by first moving the carriage 18 to the next broken yarn spindle by means of the handle 65. The operation of returning the nozzle 80 (FIG. 5) may be performed either subsequent to the completion of the yarn joining operation or after passing the auxiliary yarn through a traveller and winding its end on a bobbin. This operation is performed in a condition in which both the operating lever 86 and the handle 87 (FIG. 5) are held by hand. Then, the handle 87 is raised a little and the slide 76 is raised until the latch 84 automatically engages the apertured portion 85.

In the above embodiment, the roller 49 is shown as a yarn joining device; and the movement of the carriage 18 and of the arm 32 are all made by hand; a structure comprising the spindle 25, the movable arm 23, the spindle holder 24, the operating plate 29, the arm 28, the movable body 39 and the detect portion 44, is shown as a device for fixing the location of the carriage 18; and the movable body 39 is shown as a device for simultaneously releasing latch 35 and locking the location fixing device. But it should be noted that the present invention is not confined merely to the embodiment just described. For example, the movement of the carriage 18, the location fixing movement, the movement of the arm 32 can all be automatically performed.

In short, apparatus for joining ends of yarn for a spindle of a spinning frame has the following construction: An arm provided with a yarn joining device is pivotally supported by a carriage which is freely movable along spindle rails; a latch is provided to prevent the arm from moving except during the yarn joining operation; a location fixing device is provided to establish a fixed location of the carriage relative to the spindle in a condition in which the yarn joining device is located at a predetermined location relative to the carriage; and a device is provided to simultaneously lock the location fixing device and release the latch means. Thus, the apparatus of the first embodiment of the invention has the following advantages: One apparatus of the present invention is able to take care of yarn joining operations for several spindles. As compared with one such apparatus for each spindle, the former is more economical. In addition, unless the location of the carriage is fixed at a predetermined location, the arm or the yarn joining device is unable to move. Thus, the yarn joining device is moved by the arm only in a predetermined direction relative to the carriage. Therefore, the direction in which the yarn joining device moves and the location thereof when yarn joining operations are performed are the optimum direction and location for yarn joining operations. Even in the case of operating the arm, only a little practice will be enough for operatives to perform yarn joining operations, easily and accurately. Besides, after the location of the carriage is determined, there are less errors in operation than in the case of disengaging the arm mechanically. The apparatus of the present invention can be handled safely and at least one step of its operation can be omitted, and efficient operations can be performed with facility.

In particular, as described in the example of the present embodiment of the invention, the apparatus is more conveniently employed when it is so constructed that the releasing of its fixed position can be automatically performed with the movement of the arm. But it can be more safely handled when it is so constructed that releasing its fixed position is performed after the arm has returned to its original position.

In this first embodiment, the plate 62 is so arranged as to be incapable of resilient displacement in a vertical direction, but it may be so arranged as to allow a vertical resilient displacement, so that even in a case where there is danger that it comes into contact with, e.g. the flute 91 or the lower front roller 90, it is possible to prevent an improper force from acting on the plate 62 or the part to which it is attached.

Further, in case the plate 62 is made of an elastic element such as of rubber, with the front edge thereof being provided with no notch or the like as in the embodiment shown, and the front end is parallel to the axis of the pressing roller 49 and is brought into contact with the strand being sucked into the flute 91, it is still possible to spread the strand so that the strand may be contacted with the auxiliary yarn.

A. YARN SUPPLIER-SECOND EMBODIMENT OF INVENTION SHOWN IN FIGS. 13-35

The automatic yarn-piecing system embodied in accordance with the invention is composed of an auxiliary or pilot yarn supplier to a traveller, another yarn supplier to the said auxiliary yarn supplier, and a piecing unit of the auxiliary yarn and a roving. The following description is to explain each part and element of the system.

As is shown in FIG. 13, a frame 101 is movably mounted on the guide rails L¹, L² provided along the spindle rail of the spinner and driven along said rails by means of a drive unit not shown in the drawing. On the lateral side portion of said frame 101 is secured a spindle 103 sustaining the auxiliary or pilot yarn bobbin 102 and above this bobbin 102, a yarn clip 113 is provided as is shown in FIG. 18. Said clip 113 includes a resilient element 105 provided on an element 104 carried on frame 101' which is secured to said frame 101 and a movable yarn-picker 106 for pressing the yarn against said resilient element 105. Said movable yarn-picker 106 is provided on the upper edge of a rod 106' supported on the frame 101' by pivot 107, and is arranged to be pressed against said resilient ele-

ment 105 by means of a spring 108 positioned between the frame 101' and the rod 106'.

Element 104 is provided with a slit 109 for guiding the yarn to be transferred upward between the resilient element 105 and the movable yarn-picker 106. Said rod 106' includes in the free portion of its lower end, as is shown in the FIGS. 33 and 34, a cam roller 112 engageable with a first cam 111 secured on a drive shaft 110 journaled on the rear of the frame 101. As is shown in FIG. 14, an instant supplier 136 of a fixed length of the yarn includes a split V-shaped pulley 116 and a vertical tubular shaft 115 mounted for rotary and axial movement in the bearing 121 secured on the upper edge of said frame 101'. The lower portion 117 of said split V-shaped pulley 116 is secured on the shaft 115 while the upper portion 118 is secured on a tubular shaft 120 which telescopes into the shaft 115. Said lower portion 117 is pressed against the upper portion 118 by means of a spring 122 provided between the bearing 121 and lower portion 117. Said shaft 115 has a driven gear 123 secured to its lower portion, and on the upper planar surface of this driven gear 123 is positioned the free end of a lever 124 which is arranged to move the shaft 115 and its portion 117 down against the force of spring 122. Said lever 124 is supported on the arm 114 by means of a pivot shaft 125 and is connected to the upper end of the wire 127 slidably mounted in tube 126 secured at its upper end on the frame 101'. The spring 128 is mounted between the lever 124 and the upper end of the tube 126 to force the lever 124 upward.

As is shown in FIG. 34, the second cam 129 secured on said drive shaft 110 actuates said wire 127 through a corresponding lever 131 connected to the lower end of wire 127 and having a subordinate roller 130 engageable with the second cam 129. Reference numeral 132 in FIG. 13 designates an air supply pipe which jets air downward into said shaft 115 and which is inset into a cylindrical body 133 connected to a bearing 119. Reference numeral 134 designates a tubular guide to lead the supply of yarn which has been led upward from the slit 109 of said clip 113 to said V-shaped split pulley 116 with said tubular guide being connected to the frame 101' through a stay 135. A vertical yarn supply conduit 137 is positioned in spaced relation below the lower end 115' of said shaft 115, and as is shown in FIG. 13, supported on the frame 101' by means of a stay 138. Said yarn guide conduit has through its full length a slit 139 permitting withdrawal of the yarn therefrom and spaced from the lower end 140 of this yarn guide conduit 137 is situated a flat plate 141 secured to the upper end of a rod 143 slidably mounted in a vertical cylinder 142 provided on said frame 101'. On this flat plate 141 is secured a suction duct 144 coaxial with said source yarn guide pipe 137 and connected with a suction pipe 145. The functional effect of the aforementioned yarn supplier is as described in the succeeding explanation.

By way of further explanation, suppose that the yarn supply which is pulled out from said yarn bobbin 102, passing through slit 109 of clip 113 and then through guide 134, is wound to fixed quantity on the V-shaped split pulley 116. The length of the wound yarn is equal to the distance from the position of this V-shaped split pulley 116 to a position below the upper outlet of said suction duct 144. In this position the drive shaft 110 shown in FIG. 34 drives the cam 111 to allow the spring 108 (FIG. 18) to rock the rod 106' under control of roller 112 (FIG. 34) whereby the movable yarn-picker 106 separated from the resilient element 105 is pressed against the side thereof and holds the yarn which is being guided upward. The second cam 129 shown in FIG. 34 rocks a responsive lever 131 downward through the subordinate roller 130 thereby pulling down the wire 127 (FIG. 14) against the spring 128 thereby driving the lever 124 downward, thereby separating the pulley portions 117, 118 sufficiently to provide a passage for the yarn from the pulley into shaft 115.

Air jettied out of an air-supplying pipe 132 passes through the shaft 120 to said shaft 115 producing a suction, so that the supply of yarn T reserved in said split pulley 116 is pulled out into the shaft 115, thus causing it to travel through yarn guide

conduit 137 along with air stream passing therethrough. The yarn supply extending from the lower end 140 (FIG. 18) of said guide conduit 137 is drawn by the suction duct 144 and pulled out in a straight line. When this takes place, clip 113 serves to prevent any more yarn from being drawn out. Shaft 115 and conduit 137 together constitute a narrow space or passage in which yarn T is accumulated and held under tension after being drawn from the split pulley. As has been mentioned, after the supply of yarn T is pulled through the conduit 137, the second cam 129 in FIG. 34 allows the wire 127 (FIG. 14) and the lever 124 to return to their original positions. The shaft 115 and the lower pulley portion 117 are urged upwardly by means of the spring 122, thus closing the V-shaped split pulley 116 thereby pressing the yarn T between the two halves of the pulley.

B. AUXILIARY YARN SUPPLIER TO A TRAVELLER

The system for supplying the yarn to a traveller will now be explained.

The flat plate 141 shown in FIGS. 18 and 20 moves up and down along with the ring rail 146. However, said flat plate 141 is set on the ring rail 146 in such a manner that it can move laterally along the full range of the spindles carried by the spindle rail. As is shown in FIG. 19, a segmental arm 149 having the yarn supplier 148 at its edge is pivoted at 147 upon the flat plate 141. A guide 150 for transferring the supply of yarn is provided adjacent the end of the path through which supplier 148 moves in pulling out the supply of yarn. This transferring guide 150 includes upper and lower guide plates 151, 152 and retainer 154 pivoted therebetween at 153 (see FIG. 19) and movable with respect to the transferring path of said yarn supply holder 148. The retainer 154 is held by means of leaf spring 155 in opposition to the transferring path of the yarn holder 148, and includes an arcuate portion 154a and a yarn sustaining lip 154b, thereby making it possible to pass through this retainer 154 the yarn supply which is being held and pulled out by means of said yarn holder 148 and provides resilient means to prevent yarn T from moving back along with the retrogression of the yarn holder 148.

The segmental arm 149 has a normal position which is laterally outwardly from the position of the upper opening of said suction duct 144 and moves through an arcuate path in order that by means of the yarn holder 148 it draws out a portion of the supply of yarn held in the suction duct 144 and then supplies the yarn to the transferring guide 150 so that it will transfer therethrough. As is shown in FIG. 20, a yarn cutter 164 includes a holding plate 156 having a downwardly facing edge 157 for holding the yarn, a receiving knife 159 and a slideable knife 163. The holding plate 156 is carried near the suction duct 144 on the free end of an elongated plate 158 which is secured on said flat plate 141, almost perpendicularly with respect to the direction in which the flat plate 141 is transferred laterally. Also, on said free end of the elongated plate 158 is secured the receiving knife 159 for cutting the yarn which is held by said edge 157. The slideable knife 163 is mounted on the front edge of a slideable plate 162 which is movably arranged with respect to the receiving knife 159 in said projected plate 158 by means of slots 160 and pins 161.

The intermediate portion of the yarn supplied to the transferring guide means 150 by means of said segmental arm 149, as is shown in FIG. 19, is advanced near the ring 165 on said rail 146, and opposite to the side where said suction duct 144 is located. For this purpose, a reciprocable rod 166 is secured on a holding element 167 provided on the flat plate 141. The reciprocable rod 166 has in its front end a notch 168 which is arranged to engage with the yarn T as is shown in FIG. 18. The position to which this notch 168 may be advanced is such that the yarn forwarded to the side of the ring 165 is supplied to the course of the traveller 169 and engaged therewith. A rockable arm 171 also has a reciprocable motion because of the manner of its attachment to plate 158. As shown in FIG. 20, this arm has in its foremost end a kerf 170 which, when in a down posi-

tion (not shown), lies adjacent to said holding plate 156 of the yarn supply and is then near the ring 165. As will be seen from FIGS. 18 and 19, the arm 171 is supported rearwardly of said projected plate 158 by means of a pivot 172 and may be moved into an upward position. A pin 174 projects from slideable plate 162 and engages with cam slot 173 in arm 171 and said cam slot 173 is so constructed as to cause the arm 171 to rock as said slideable plate 162 advances and retracts. An air-jetting nozzle 176 (FIG. 18) which is positioned to jet air between said suction duct 144 and a spindle 175 jets air partially downwardly. This air-jetting nozzle 176 is mounted on flat plate 141 by means of a holder 177 and connected to an air-supplying pipe 178. A vertical plate 179 is integrally mounted on arm 149 in such a manner that the yarn holder 148, as shown in FIG. 19, returns to its normal position outside of the suction duct 144 and plate 179 is situated just in front of the air-jetting nozzle 176 to prevent air from being jetted out toward the spindle 175.

The driving system of the aforementioned elements operates as follows. Firstly, the slideable plate 162 of the yarn cutter 164 is connected by means of the wire 184 slideable in tube 183 to a lever 182, as shown in FIG. 34, which moves through a cam roller 181 yieldingly held by spring 194 in engagement with a third cam 180 secured on said drive shaft 110. The slideable rod 166, shown in FIG. 19, is connected by means of the wire 189, slideable in tube 188, to a lever 187 which moves through a cam roller 186 yieldingly held by spring 197 in engagement with a fifth cam 185 secured on said drive shaft 110. The segmental arm 149 has adjacent its pivot 147 a narrow slot 192 which cooperates with a pin 191 which protrudes from a slideable element 190 which is supported for forward and backward slideable motion substantially in parallel to the forward and backward slideable motion of rod 166, all of which is shown in FIG. 19. The construction is such that said slideable element 190 moves in unison with the slideable plate 162 the leg or projection 162' on plate 162 being connected to element 190 by pin 193.

It is to be observed also that the forward movement of said slideable plate 162, the upward motion of the rockable arm 171 made in accordance therewith and also the return of the segmental arm 149 are all caused by a helical spring 195 (FIG. 34) mounted between the slideable element 190 and the flat plate 141 in FIG. 19. At the same time rod 166 is moved forward by helical spring 196 which is mounted between the rearward portion of rod 166 and the flat plate 141. As shown in FIGS. 33 and 34, the lower ends of the tubes 183, 188 and 126 are attached respectively to a U-shaped frame 199 mounted on shaft 110 by bearings 198. The upper ends of the tubes 183, 188 are attached respectively to a U-shaped frame 200 connected to said flat plate 141 as shown in FIG. 19. Levers 131, 182 and 187 respectively are supported upon a lateral shaft 202 held in the lower portion of said frame 101 by bearings 201 just as shown in FIGS. 33 and 34.

Shown at 203 in FIG. 14 is an upper segmental arm whereby the yarn drawn into the conduit 137 from the shaft 115 is pulled out laterally from the position intermediate shaft 115 and conduit 137 and its movement is synchronized with the movement of arm 149.

Said upper segmental arm 203 is situated at the upper side of a fixed flat plate 204 which extends forwardly from the upper end of said frame 101' and at the same time is supported by means of a pivot 206 upon a supporting plate 205 arranged rearwardly of the frame 101'. The forward end of said arm 203 includes a yarn holder 207 as is shown in FIG. 15. The wire 209 slideable in tube 208 is connected to arm 103 and has its other end connected to a lever 212 (FIGS. 33 and 34) supported on shaft 102 and carrying a cam roller 211 held by a spring 214 in engagement with the cam 210 secured on the drive shaft 110. The lower end of the tube 208 is attached to said U-shaped frame 199, while the upper end thereof is attached to said supporting plate 205. The lever 212 moves the upper segmental arm 203 shown in FIG. 15 from and to its original position or the position where it abuts against a stop 213 which projects from the flat plate 204.

As shown in FIG. 15, the flat plate 204 has a notch 217 which prevents the yarn from following the returning motion of the upper segmental arm 203. The functional effect of the yarn supplier to a traveller constructed in the above-mentioned method is as follows. As has been mentioned, in the event the yarn has been supplied into the air stream, the upper segmental arm 203, with reference to FIG. 22 and the timing graph 35A and B, is so situated that the yarn holder 207 is positioned at the lateral outer side of the middle portion 5 between the longitudinal shaft 115 and the yarn guide conduit 137, and the segmental arm 149 is then in normal position that the yarn holder 148 is positioned at the lateral outer side of the opening of the suction duct 144. At this time, the upward rockable arm 171 is at its highest position. Thus the slideable plate 162 (FIG. 20) of the yarn cutter 164 is then in the most extended position attainable where the yarn has been cut with the slideable knife 163. Meanwhile, the slideable rod 166 shown in FIG. 19 is now in a position where it has been retracted fully by means of the cam 185 shown in FIG. 34. Due to the position of the segmental arm 149, the plate 179, shown in FIG. 19, situated just in front of the nozzle 176, prevents the air jet from rotating the traveller 169.

Though the above-mentioned function of the yarn supplier has been terminated in holding the yarn when V-shaped split pulley 166 in FIG. 14 was closed, yet in synchronism with the closing of this split pulley, the third cam 180 in FIG. 34 pushes down the lever 182 against the helical spring 194 through the cam roller 181, pulling the wire 184 to move back the slideable plate 162 (FIG. 19) rocking the segmental arm 149 toward the transferring guide 150 through the pin and slot connections 191, 192 against the helical spring 195. Simultaneously the sixth cam 210 (FIGS. 33 and 34) pushes down the lever 212, and pulls the wire 209 to rock the upper segmental arm 203 (FIG. 15) in the same direction as the segmental arm 149.

Consequently, the yarn T in the air stream as shown in FIG. 23 is hooked by the yarn holder 207 of the upper segmental arm 203 and the yarn holder 148 of the segmental arm 149 is pulled out laterally from a slit 139 (FIG. 18) of the yarn guide conduit 137. Then the yarn T as shown in FIG. 24 is pulled out by means of the segmental arm 149 and held fast so as not to get out of the transferring guide 150 until it pushes aside the holder 154 of the transferring guide 150, and enters between the guide plates 151 and 152 (FIG. 19).

By this time, the rockable arm 171 (FIG. 20) has returned to a lower position than that of the yarn T which reaches the transferring guide 150 from the suction duct 144, while the slideable plate 162 is in its rearward position. A little before the segmental arm 149 supplies the yarn T to the transferring guide 150, the fifth cam 185 begins to release the lever 187 so that spring 196 can move rod 166 (FIG. 19) forward. Following this, the slideable plate 162 (FIG. 19) is allowed to advance by means of the helical spring 195 through the third cam 180 and as a result, the segmental arm 149 is restored to its home position. When the slideable plate 162 has advanced to some extent, the rockable arm 171 starts rising under influence of the pin 174 riding in the slot 173. By this time, the reciprocable rod 166 has engaged in notch 168 the yarn T which extends from the suction duct 144 to the transferring guide 150 (FIG. 18) and pushed to a position (FIG. 25) where it can move along the transferring course of the traveller 169 of the ring under the influence of the air jetted from the nozzle 176 (FIGS. 18, 19) and thus the traveller is automatically engaged with the yarn T extended along ring 165. As soon as the segmental arm 149 begins moving, the plate 179 (FIGS. 18, 19) has left a position adjacent to the mouth of the nozzle 176. Therefore, part of the jetted air streams within the ring 165 to rotate the traveller 169. As shown in FIG. 26, the yarn T which is pushed forth by means of the reciprocation of rod 166 in the aforementioned manner is so positioned below the edge 157 of the holder 156 that the yarn T positioned between the traveller 169 and edge 157 is hooked and raised by the notch 170 of the rockable arm 171. While the above-mentioned functions are taking place, the segmental arm 203 remains stationary in the position where it has now pulled out

the yarn T. Immediately before the segmental arm 149 returns clearly to its home position and the rockable arm 171 lifts the yarn T up to its highest position, the yarn which extends from the edge 157 to the suction duct 144 is cut by the slideable knife 163 between the receiving knife 159 (FIG. 20) and said knife 163 (FIG. 27) that is arranged in the foremost end of the slideable plate 141. Moreover, when the upper segmental arm 203 moves in a lateral direction, the segmental arm 149 also moves in a lateral direction and when the rockable arm 171 moves in a longitudinal direction, the V-shaped split pulley (FIG. 14) is closed to hold yarn T fast so that the lower portion of the yarn drawn into the suction duct 144 is then pulled out.

After the yarn is cut in this manner, the cut side thereof is facing along the path of the traveller and is in such a position that it is placed around the rotating bobbin B, as shown in FIG. 28, by reason of the air jetted from nozzle 176 (FIGS. 18, 19).

At this time the length of the yarn which extends from the traveller 169 is almost equal to the length by which the former is raised by means of the rockable arm 171, this being preferably the length which approximates the circumference of the bobbin B. The reciprocable rod 166 moves back against the helical spring 196 through the wire 189 by means of the lever 187 which is pushed down by the fifth cam 185 (FIG. 14).

Accordingly, as this operation progresses and as the extra portion of the yarn is pulled out by the air jet, it is hooked by means of the forward reciprocable rod 166 between the traveller 169 and the transferring guide 150. However, said extra portion of yarn is not now in a position to be wound onto the bobbin B. When said reciprocable rod 166 is moving back, the lower pulley portion 117 of the split pulley 116 (FIG. 14) is pushed down again by means of the second cam 129 (FIG. 34) in the manner as has been mentioned above, and allows the yarn T to be pulled out. At this time, the clip 113 (FIG. 18) is released from holding the yarn T through the first cam 111 (FIG. 34). Then the upper segmental arm 203 is allowed to move back by means of the helical spring 214 in cooperation with the sixth cam 210 and returns to its home position as shown in FIG. 30. As has been set forth, the yarn T has its extra portion pulled out and around the bobbin B along with the returning motion of the upper segmental arm 203. But due to the friction which increases more and more between the bobbin B and the yarn T, a greater quantity than said extra portion of the yarn is pulled out from the yarn bobbin 102 through the clip 113 and the V-shaped split pulley 116. As is illustrated in FIG. 31, the friction between the bobbin B and the yarn T increases and the yarn T is rapidly reeled onto the bobbin B about at the time when the upper segmental arm 203 moves past the notch 217 in the reverse direction and the yarn T is hooked by the yarn holder 207 and is transferred into the notch 217 and held. At this time, the yarn T is under considerable tension and consequently the holder 154 of the transferring guide 150 is pushed aside forcibly against the plate spring 155 (FIG. 19). This action instantaneously removes tension in the yarn T being transferred thereby making it possible to reel the yarn onto the bobbin B without breaking (FIG. 32).

Subsequently, the reciprocable arm 203 (FIG. 15) returns to one side of the yarn guide conduit 137 and abuts against the stop 213. As indicated hereinbefore when the segmental arm 149 (FIGS. 18, 19) has returned to its home position, the plate 179 prevents air from being emitted from nozzle 176 toward the spindle.

C. PIECING SYSTEM FOR ROVING AND YARN SUPPLY

As shown in FIG. 14, the guide rail 219 is secured on frame 101 in approximately the same elevation as that of the lower drive roller 218 of the front roller mechanism generally denoted as 216 and arranged in the drafting frame 215. A flat plate 220 located to one side of this guide rail 219 includes rollers 223 which engage with both the upper guide channel

221 and the lower guide channel 222 of guide rail 219 and is so constructed that it can move forwardly and backwardly along guide rail 219.

The laterally extending plate 224 shown in FIG. 16 projects outwardly from said flat plate 220 and is provided in its front edge portion with both a press roller 225, supported on a lateral shaft 226, and a laterally resilient arm 228, the rear end of which is mounted on lateral plate 224 through a mounting element 229 and the free front end is connected to a flat angular plate 227 positioned below said press roller 225. As shown in FIG. 17, a channel-shaped frame 230 is provided on said lateral plate 224 adjacent to the lower portion of said resilient arm 228. Said movable plate 227 is provided with a slit 231, having a frontal release, positioned below the center of the press roller 225 and also provided with converging edges 232 extending forwardly and mutually alongside of said frontal release of slit 231. Said slit 231 has in its inner part a thread guide 233. Moreover, slit 231 is narrowed to such an extent that while preventing the untwisted fibrous strand or roving to pass therethrough, it will allow said yarn to pass through. The press roller 225 is in such a position that it can abut against said drive roller 218 (FIG. 14) by means of movement of the plate 220 which is situated in such a manner that plate 227 moves between the drive roller 218 and the flute 234 of the pneumatic clearer provided below drive roller 218 when the press roller 225 is in engagement therewith. In FIG. 14 the means defining a suction hole for the flute 234 is designated as 235. Said flat plate 220 is connected through a link 241 to a driven lever 240 fixed to an intermediate rock shaft 239 to which is fixed a lever 238 moving through the cam roller 237 in engagement with the fourth cam 236 secured on the drive shaft 110 as shown in FIGS. 33 and 34. As is also shown in FIG. 33, this plate 220 is influenced by means of a helical spring 242 mounted between the lever 240 and the frame 101. Said intermediate shaft 239 is supported on the bearing plate 243 which extends from frame 101. The piecing system of the roving and the yarn T constructed in conformity with the aforementioned manner has the following functional effect.

40 The yarn T being reeled onto the bobbin B through the traveller 169, by means of the above-mentioned yarn supplier for the traveller, is automatically transferred into a pigtail guide 244 (FIG. 18) which is accurately positioned over the spindle 175. When the yarn is moving downward almost in a straight line between the guide 244 and the notch or recess 217 (FIG. 15) of the flat plate 204, the fourth cam 236 allows the driven lever 238 and the lever 240 to be rocked forwardly by reason of the helical spring 242, and the longitudinal flat plate 220 advances along the guide rail 219 under influence of lever 240. Consequently the yarn T which trails almost perpendicularly from recess 217 is engaged by press roller 225 and pushed out to the side of the drive roller 218 (FIG. 14). At this time, the yarn T collides with the left hand one of the converging edges 232 (FIGS. 15 and 16) of the movable flat plate 227, resiliently shifting this flat plate 227 toward the left side causing the yarn to be transferred into the slit 231. Right after the press roller 225 has commenced advancement, the second cam 129 (FIG. 34) releases the inner wire 127 and the lever 124 and lets spring 122 move the lower pulley portion 117 of the V-shaped split pulley 116 to abut against the upper pulley portion 118 thereof again, thereby stopping the drawing of the yarn T. This functions to rotate the traveller 169 at the same velocity as the bobbin B with the result that the yarn T is tightly twisted. Therefore, when the yarn T abuts on the press roller 225, it moves along on the press roller 225 with the movable flat plate 227 to the right (FIG. 15) in case of Z-twisting. When the yarn T has reached near the center of the press roller 225, namely when it is opposite the approximate center of the range wherein the roving traverses on the drive roller 218, the press roller 225 is placed in resilient engagement with the drive roller 218. At this time, the guide edge 232 of the movable flat plate 227 coming between the drive roller 218 and the flute 234 have already abutted against the roving F which is pulled out from between the drive roller 218 and the

top roller 216' and has now been drawn into the suction hole 235 of the flute 234. Thus, the linear transfer of the roving F into the suction hole 235 from the periphery of the drive roller 218 is obstructed so that the roving F which is drawn out through the drive roller 218 is extended through a movement laterally of the movable flat plate 227 and abuts upon the yarn T passing through the slit 231. At this time, the yarn T being tightly twisted, now becomes twisted with roving F. The portion of the roving F in the flute 234 is separated from the remainder. It goes without saying that the aforementioned functions are not necessary and the roving F will be twisted instantaneously with the yarn if the roving on the drive roller 218 conforms to the yarn T on the press roller 225.

However, on more than one occasion the position of the roving F is displaced laterally of that of the yarn T the very moment the press roller 225 abuts against the roving F because the latter is traversing to and fro on the drive roller 218. Even in this case, the roving F has a portion at least twisted with the yarn T due to said movable flat plate 227. The moment the press roller 225 abuts on the drive roller 218, it forcibly jerks the yarn T in its side connected within the shaft 215 through the rotation of the press roller 225 whereby the yarn T is broken or separated intermediate the press roller 225 and the V-shaped split pulley 116 holding the yarn T and specifically intermediate the press roller 225 and the lower end 115' of the longitudinally cylindrical shaft 115.

Immediately after the press roller 225 has abutted against the drive roller 218, both the press roller 225 and the movable flat plate 227 are separated from the drive roller 218 (FIG. 14) because the longitudinally flat plate 220 is forcibly moved back by means of the fourth cam 236 in FIGS. 33 and 34 through the driven lever 238 and the lever 240. The breaking of the tightly twisted yarn T causes it to untwist and its separated portion gets twisted with the roving F being drawn out successively with the result that the yarn T is pieced together with the roving F which, then being twisted up, is pulled toward the traveller 169. Incidentally, when the movable flat plate 227 moves back, the roving F twisted on the yarn T is drawn into the thread guide 233 together with the yarn T. Accordingly, in case the roving F has traversed to the fullest extent along the drive roller 218 and if the movable flat plate 227 were fixedly secured, the roving F would be extremely bent in the lateral direction with a very short range of longitudinal movement when this movable flat plate 227 moves back, consequently, giving rise to the snapping of the strand. Due to the resilient arm 228 holding the movable flat plate 227, this plate is shifted laterally by the yarn which resists any tendency to be deflected from the straight line connecting the guide 244 to its abutting point on the drive roller 218, thereby avoiding the snapping of the strand. After the V-shaped split pulley is closed, the shaft 115 is rotated for a predetermined interval by means of a suitable motor through a driven gear 123 to rotate the V-shaped split pulley 116 so that on the circumference of the V-shaped split pulley 116 is reeled a determinate length of the yarn to be instantaneously supplied into the air stream when the succeeding operation sets in. (The specific means for driving gear 123 is no part of the claimed invention, but it is obvious to one skilled in the art that the provision of such means would require nothing more than the exercise of mechanical skill. For example, an electric motor might be operatively connected to gear 123 by a gear train of a ratio such that the energization of the motor for a predetermined interval would effect a sufficient number of revolutions of the split pulley to wind the required length of yarn T. The motor switch could be operated at the appropriate points in the cycle (FIG. 35B) by a cam on shaft 110. The modified split pulley of FIGS. 41 and 42 could be similarly driven.)

Said drive shaft 110 in FIGS. 33 and 34 is automatically intermittently rotated by a motor not shown in the attached drawings. Furthermore, this yarn-piecing system transferring along the line of the spindles is provided with a detection unit which senses the working condition of the detector installed to detect a snapped yarn on the yarn spinner.

According to some well known techniques it is easily possible to embody such a construction that the yarn-piecing system automatically stops just in front of a spindle and the drive shaft 110 automatically makes a single rotation initiated by means of said detection unit, and after the drive shaft 110 has been driven to make a single rotation, the yarn-piecing system resumes advancement. Incidentally, this yarn-piecing system is applicable not only to the work of initially putting yarn on an empty bobbin, but also the work of piecing yarn whenever it is snapped while being spun. (It does not mean piecing the snapped yarn by drawing the wound yarn out of the bobbin but it means piecing the snapped yarn by joining it to the auxiliary yarn.)

The movable flat plate 227 shown in FIG. 16 lies in a horizontal plane perpendicularly with respect to the length of yarn. But it could also be inclined with respect thereto. Although this has a notch fashioned into a L-shaped form with the guide edges 232 and the slit 231, yet it may also be replaceable with a notch of V-shaped form. The notch of any form mentioned above has its inner part engaged with the twisted yarn so that it can be pressed against the roving F to secure the twisting of this roving F with the yarn T.

THIRD EMBODIMENT OF THE INVENTION SHOWN IN FIGS. 36-40

This embodiment is concerned with apparatus which directly works for joining the auxiliary yarn with the fibrous strand or roving, as shown in FIGS. 36-40, and is also applicable to the yarn piecing-up machines already described in the first and second embodiments.

This embodiment will now be described in detail with reference to the drawings. As shown in FIG. 36, a pneumatic flute 303 having an opening 304 for sucking a broken strand F is provided below a driving roller 302a of a pair of front rollers 302 for a draft means 301 in a fine spinning frame. And a machine frame 305 positioned in front of said front rollers 302 has two long guide rods 306 extending in a direction substantially at right angles with the axes of said front rollers. A movable frame 307 which is free to slide toward and away from said guide rollers 302, as guided by said guide rods 306, has a pressing roller 309 journaled at the front end of the frame by a transverse shaft 308, an auxiliary yarn suction nozzle 310 positioned substantially medially above the pressing roller 309 and at a position somewhat remote from the front rollers 302 when in operative position (FIG. 37) and a strand suction nozzle 311 positioned below and substantially medially the width of the pressing roller 309, said two suction nozzles 310 and 311 communicating with a suction tube 312 fixed to said movable frame 307. A cylindrical body 314 is pivoted to said movable frame 307 through a transverse shaft 313, and a spring 316 is interposed between said cylindrical body 314 and a shaft body 315 slidably positioned within said cylindrical body 314 and acts to push out said shaft body 315. The outer end of said shaft body 315 is connected to the upper end of a reciprocating drive body 318 by a transverse shaft 317. A movable frame 307 is mounted on the upper part of said movable frame 307 through the medium of two spaced pins 319-319 and aligned elongated openings 320-320 in such a manner as to be free to reciprocate in a direction parallel to the direction of movement of said movable frame 307. An auxiliary yarn cutting blade 322 is attached to the upper part of the front end of the movable plate 321 and cooperates with a planar V-shaped receiving blade 323 attached to the upper part of the front end of said machine frame 305 to cut an auxiliary yarn T. A spring 324 serving to retract the movable plate 321 with respect to the movable frame 307 is interposed between the movable plate 321 and one pin 319 fixed to said movable frame 307. A driven pin 325 projecting from the rear end of said movable plate 321 receives a thrust at its rear side produced by a transmission lever 326 associated with said shaft body 315.

As shown in FIG. 39, said auxiliary yarn suction nozzle 310 has at its front end part an auxiliary yarn suction and guide

groove 310a extending from its front surface to its upper surface, and the front end opening 311a of the strand suction nozzle 311 has a pointed upper end, as shown, positioned closely adjacent to the pressing roller 309, said opening 311a being inclined in such a manner that when the pressing roller 309 abuts against the lower driving roller 302a of the front rollers 302 and 302a, nozzle 311 moves the strand away from the roller 302a. The peripheral surface of said pressing roller 309 is provided with a shallow groove 309a positioned centrally thereof so as to lie on a line passing through the opening 311a and the guide groove 310a, in which groove 309 the auxiliary yarn will fit.

As shown in FIG. 36, if strand F delivered from the pair of front rollers 302 breaks on its way to a bobbin onto which it is to be wound, it is sucked into a suction opening 304 of a flute 303. On the other hand, the auxiliary yarn T is now taut and extending from an upper particular position to a lower particular position over the front part of the pressing roller 309 retracted with respect to the front rollers 302. In case the strand F breaks, as mentioned above, the lower end part of the auxiliary yarn is passed through the traveller and wound onto the bobbin manually or by other suitable means. In this condition, the reciprocating drive body 318 is moved forwardly, whereby, as shown in FIG. 37, the movable frame moves forwardly while at the same time it is guided by the guide rods 306 so that it is pressed against the roller 302a. In this forward stroke of the pressing roller 309, the auxiliary yarn T comes into contact with the front surface of the pressing roller 309 and, while then being held taut, is pressed against the side of the lower strand delivering roller 302a. At this time the abutting position of the auxiliary yarn with respect to the pressing operation should be located at a position somewhat nearer to one side of the pressing roller 309 rather than at said shallow groove 309a provided therein so that the auxiliary yarn rolls on the front surface of the pressing roller 309 toward said shallow groove 309a owing to the twist imparted by the rotation of the traveller. Thus, if it is so arranged that the auxiliary yarn T falls into the groove 309a, further rolling of the auxiliary yarn T is prevented. As the pressing roller 309 approaches the strand delivering roller 302a, the yarn above the level of the pressing roller 309, i.e. the feed source side, abuts against the V-shaped edge of said V-shaped receiving blade 323 and is guided into the innermost part of the V-shaped edge and its position becomes established so that the portion of the auxiliary yarn between the receiving blade 323 and pressing roller 309 will automatically fall into the suction guide groove 310a of said auxiliary yarn suction nozzle 310. On the other hand, when the pressing roller 309 abuts against the roller 302a, the suction opening 311a approaches the strand F sucked from the strand delivering roller 302a into the flute 303, so that the so that the strand F is pulled away from the flute 303 and sucked into the suction nozzle 311. Furthermore, as shown in FIG. 37, that portion of the auxiliary yarn T fitted in the groove 309a which is nearer to the traveller has its position established by the groove 309a and has passed by the central front part of the opening 311a of said strand suction nozzle, with the result that the strand sucked into the strand suction nozzle is brought into engagement with at least that particular portion without fail. The reciprocating drive body 318 swings forwardly even after the pressing roller 309 abuts against the strand delivering roller 302a so that the shaft body 315 alone is advanced while compressing the spring 316, with the result that the transmission lever 326 connected to the shaft body 315 pushes the driven pin 325 of the movable plate 321 to advance the movable plate 321 against the spring 324. As a result, the auxiliary yarn cutting blade 322 is advanced and cooperates with the V-shape notched receiving blade 323 to cut the auxiliary yarn T positioned in the recess thereof. The portion cut off from the auxiliary yarn, i.e. the free end portion above the level of the pressing roller tends to deflect transversely because of the twist imparted thereto. However, since it is fitted in the suction guide groove 310a of the auxiliary yarn suction nozzle, it is reliably sucked into the suction

nozzle 310, whereby the deflection of the free end portion of the auxiliary yarn T is prevented. In this condition, the pressing roller 309 is subjected to the rotation of the strand delivering roller 302a and acts to deliver the cut auxiliary yarn T and strand F, so that at the junction between the auxiliary yarn T and strand F, the auxiliary yarn T is joined to the strand owing to the twist imparted to the auxiliary yarn. The reciprocating drive body 318 is retracted, followed by the retraction of the movable frame 307 to complete the piecing-up of yarn.

According to this embodiment, the following effect can be obtained. Thus, even if the strand F is traversing on the lower front roller 302a in the direction of the axis of said roller, the place where the strand is being sucked remains unchanged. If, therefore, the pressing roller is positioned to face the suction port 304 of the flute 303 when the pressing roller 309 contacts said roller 302a, the strand or roving can be drawn by the suction port 311a below the pressing roller. Therefore, the portion of the strand below the nip point between the lower front roller 302a and the pressing roller 309, as viewed in FIG. 37, can be extended along the auxiliary yarn.

In addition, the axial position of the auxiliary yarn on the pressing roller established when the pressing roller 309 contacts the lower front roller 302a, can be easily aligned with the strand suction port 311a below the pressing roller 309. This can be achieved, for example, by initially determining the position at which the auxiliary yarn is allowed to contact the pressing roller by making allowance for the amount of rolling of the auxiliary yarn on the pressing roller as caused by the twisting due to the rotation of the traveller. It is also possible to completely prevent the rolling of the auxiliary yarn on the pressing roller due to said twisting. Thus, in this way by allowing the auxiliary yarn to pass in front of the strand suction port 311a below said pressing roller 309 when the latter contacts the lower front roller 302a, it is possible to bring the strand and the auxiliary yarn into contact with each other at a place adjacent the strand suction port 311a, even if the strand deviates laterally at the nip point between the pressing roller 309 and the lower front roller 302a with respect to the auxiliary yarn. In this case, since the auxiliary yarn is given a twist by the traveller, once it contacts the strand it never fails to intertwine itself around the strand to be pieced to the latter.

Since the strand is brought toward the auxiliary yarn by sucking the strand in this manner, a most reliable piecing-up effect is achieved. Furthermore, it is most effective if the auxiliary yarn is a twisted spun yarn of short fibers such as cotton fiber. Further, the suction port 310a for the twisted spun yarn as described above has another advantage as follows: if the twisted spun yarn and the strand contact together, when the pressing roll 309 contacts with the bottom front roll 302a, it is possible to prevent the lateral translation of the twisted spun yarn from the strand suction port 311a due to an untwisting effect of the yarn end after its cutting and the delivery action of the pressing roll 309 and bottom front roll 302a, so that a releasing of the strand from the twisted spun yarn can be prevented. Also, the swing motion of the cut yarn end due to its untwisting effect being restricted by the suction port 310a for twisted spun yarn, the twisted spun yarn is kept in a predetermined position, i.e. in front of the strand suction port 311a, until the cut yarn end passes downwardly through the nip point between the pressing roll 309 and the bottom front roll 302a, so that the contact of the twisted spun yarn to the strand can be prolonged to make a perfect piecing possible.

Further, the shallow groove 309a on the pressing roll 309 can produce additional holding effect for the twisted spun yarn at its predetermined position. On the other hand, a suction port 310a for twisted spun yarn end can take a narrow slit form to reduce further the swing motion of the cut yarn end due to its untwisting effect, but it is recommended to combine such suction port 310a with V-formed guide part 323 (operating at the same time as the counter blade to the cutter 322) so that the twisted spun yarn can be easily fed into the narrow groove.

The interposition of a resilient body such as spring 316 between roller 309 and drive member 318 produces the following additional effect. That is to say, the time at which the cutting means 322, 323 works is not when the pressing roller 309 is moved a fixed distance, and it does not work except after the pressing roller 309 abuts against the strand delivering roller 302a, irrespective of the amount of movement of the pressing roller 309. Moreover, when the cutting means 322, 323 works, the pressing roller 309 is under driving force transmitted thereto from the drive member through the spring so that the pressing roller resiliently abuts against the roller 302a to reliably hold the auxiliary yarn therebetween, with the result that the auxiliary yarn after being cut by the cutting means 322, 323 is reliably moved under the cooperative delivering action of the lower front roller 302a and pressing roller 309 and thus can be caused to intertwine with the strand as intended. Further, since the cutting of the auxiliary yarn is effected at a substantially fixed time with respect to the time of abutment between the pressing roller 309 and lower front roller 302a, a predetermined length of the auxiliary yarn can be caused to intertwine with the strand without bringing about a situation in which the auxiliary yarn is broken at an improper position, thus assuring a reliable and satisfactory joining between the strand and the auxiliary yarn.

Further, in a structural aspect, too, since the movement of the drive member 318 moving the pressing roller 309 against the resilient body 316 is operatively associated with the cutting means 322, 323, advantages are obtained in that the structure is simple and yet a reliable action can be effected.

The foregoing effects make it unnecessary to secure as high accuracy in the attachment of a guide rail for guiding the yarn piecing-up device, so that it becomes easier as a whole to embody automatic yarn piecing-up.

In addition, as to the cutting means and operative connectors, ones having any structure may be used. Further, as to the resilient body, rubber or the like in addition to a spring may be used. Of course, the method of interposing such resilient body is not limited to the one shown in the embodiment.

FOURTH EMBODIMENT OF THE INVENTION SHOWN IN FIGS. 41 AND 42

Referring now to FIG. 41, there is shown a modified pulley arrangement including an upper half portion 407 having oppositely disposed collars 406 and 406a respectively, the former being supported for rotation in a bearing 405 which is held in a frame 401.

The lower portion 409 of the pulley has an annular recess 409a to receive the lower tapered portion 408 of upper portion 407 and includes an elongated cylindrical throat portion 403 supported for rotation by bearing 402 and is normally urged into contact with the upper half of the pulley by a coiled spring 410 interposed between an annular shoulder provided on the lower surface of pulley 409 and the inner race of the bearing support therefor. The throat portion 403 extends beneath the frame 401 into a conduit 414 and has secured thereto a driven gear 411, as shown.

In FIG. 42 the pulley portions 407 and 409 have been moved apart by means of the pivotally mounted presser foot 412 which presses gear 411 downwardly through the medium of the wire 413, the latter being connected to and actuated by a means not shown. In this view it will be noted now that the annular recess 409a has been moved downwardly away from the portion 407, the perimeter of the tapered portion 408 of which includes a shallow helical groove 408a so that the portion Ta of thread T that has been previously wound thereon may be blown downwardly through passage 409b and then through the passage 403a in throat 403 (as indicated at 404) and out through the conduit 414 associated with the lower extremity of said throat by a stream of air emitted through the tube 415 from a source not shown.

It is believed to be apparent now to those skilled in this art that this pulley construction affords a means by which the

thread may be pulled with quickness and facility into the throat 403 by merely actuating the presser foot 412 to release the thread from being rasped between the complementary pulley parts and driving the upper part of the pulley 407 through gear 411 when it is desired to wind a predetermined length of thread in the helical groove 408a. The jet of air introduced through conduit 415 has sufficient power to remove the thread which is wound in the helical groove of element 407 and blow it down through conduit 414.

10

FIFTH EMBODIMENT OF THE INVENTION SHOWN IN FIGS. 43-48

As shown in an embodiment hereinbefore described, rove piecing may be accomplished by winding of an auxiliary or pilot yarn to the outer layer of a yarn bobbin a plurality of times after said auxiliary yarn has been joined to the broken end of a roving being fed from drafting means in a spinning frame. In this case, however, when the roving being spun into 15 yarn is wound up to form a coplike or ball-like condition but before a full bobbin is attained, the joining position with the auxiliary yarn is at an inclined surface relative to the axis passing through the center of the bobbin, for example, at the 20 position indicated at A in FIG. 43, so that a pile A₁ may be created by winding of the auxiliary yarn a plurality of times to bring inconvenience to a rewinding process in a manner that the 25 yarn provided to be rewound from a full bobbin to a cheese may get out of position from the bobbin with the pile coincident with said pile of the thread getting exposed to be 30 unwound. This reason may be considered due to the inclined surface wherein the auxiliary yarn is supplied and the pile A₁ may shift thereon without receiving any resistance in the direction of the arrow (C) when the yarn bobbin is set on a rewinder to unwind from its bobbin. In order to overcome this 35 disadvantage, it is desirable to join the auxiliary yarn at the point (D) on the bobbin wherein the pitch of the tapered line of already wound yarn is located, for in this manner the pile (D₁) is formed at a point in the bobbin (B) substantially parallel 40 to the unwinding direction, that is, to the direction of the arrow (C), to receive a frictional resistance from the curved surface of the bobbin (B) coincident with the pile (D₁) of the 45 yarn getting exposed to shift integrally when the yarn wound up to the bobbin is unwound in that direction, said resistance effective to protect the pile from integrally being taken out as a 50 whole, and eventually the yarn may be unwound in a proper manner even at the pile. This invention is to provide an apparatus effective to join the auxiliary yarn automatically at the point on the bobbin (B) wherein the extremely tapered line of 55 wound yarn is located as previously described.

An improved embodiment is shown in FIGS. 44 and 46 in which a frame 501 in FIG. 44 of the piecing-up apparatus is effective to shift in the direction of a ring rail 502. The frame 501 of this piecing-up apparatus includes a metal plate 503 which is shiftably mounted through guide members 504 for movement in a vertical direction relative to the ring rail 502. This metal plate 503 includes on its upper end a plate member 505 that is disposed on the ring rail 502, and is arranged to be effective to reciprocate in a vertical direction in cooperation with the reciprocating movement of the ring rail 502. A 60 supporter 506 having vertical slots 509 is positioned on the front of said metal plate 503 and is mounted on one of said guide members 504 by means of vertical slots 507 and attaching screw means 508 which extend therethrough whereby it may be adjusted vertically. A movable portion 511 having projections 510 is vertically slidable relative to said slots 509 and is positioned between the metal plate 503 and the supporter 506. One plane of the movable portion 511 is disposed to 65 contact directly with the metal plate 503 and is magnetically held in position by magnets 512 therein as shown in FIG. 46. Also, this movable portion 511 includes a camming means 515 whereby an actuator 514 of a first limit switch 513 which is secured to said frame 501 can be operated. Vertical slots 509 disposed on said supporter 506 are designed to have their

length substantially equal to one chase downward travel of said ring rail 502. Elements 503 to 515 inclusive may be considered as a first switch means.

The plurally slotted, as at 521, elongated flat plate 520 is adjustably secured to plate 503 by the threaded fasteners 522 and includes an angularly extending cam surface 525 adapted to operate a second limit switch 523. This second limit switch 523 is provided to open and close the circuit of the first limit switch 513, the second switch also including means effective to memorize and maintain an operational condition until a full bobbin is built and the electric power is then cut off. Elements 520 to 525 inclusive may be considered as a second switch means. The first limit switch 513 is so designed that unless the second limit switch 523 operates, the first limit switch 513 does not generate any signal even if the actuator 514 of the first limit switch 513 operates. The actuator 524 of the second limit switch 523 is operated by means of the cammed surface 525 of the operation plate 520 when the ring rail moves above the upper normal limit of its traversing movement. A fixing position of the operation plate 520 relative to the metal plate 503 is adjusted so that the cam 525 kicks the actuator 524 to operate when the upward travelling motion of the ring rail 502 takes place and exceeds the normal upper position. However, in the condition when the yarn is slightly wound on the bobbin and the inclination of a layer is not precise relative to the axis passing through the center of the bobbin, the cam 525 does not kick the actuator 524 when the travelling motion of the ring rail 502 takes place at the one chase upper position. FIG. 44 shows a condition when the ring rail 502 is positioned at the lower limit of the chase of the yarn layer wound up to the coplike or ball-like condition while the ring rail travelling motion takes place at the lower position relative to the bobbin. Consequently, as shown in FIG. 45, even when the ring rail 502 arrives at the upper limit of the chase, the cam 525 does not operate the second limit switch 523. When the second limit switch 523 does not operate as previously indicated, a piecing apparatus moves along the ring rail 502 to detect a roving breakage and then stops to generate a signal effective to start a piecing operation. In such a condition when the ring rail 502 starts its travelling motion at a position which exceeds that of a normal position, the cam 525 of the operation plate 520, secured to the metal plate 503 and effective to reciprocate in cooperation with vertical reciprocating motion of the ring rail 502, kicks the actuator 524 of the second limit switch 523 to succeed through the memory circuit the signal generated at the beginning of the operation, even when the cam 525 temporarily leaves from the actuator 524 downward. Consequently, once the second limit switch 523 has been operated as previously described, it does not start a piecing operation until the signal being generated incident to stoppage of yarn breakage detecting and the piecing-up apparatus, said signal being representative of the start of piecing operation. However, together with the signal generated by the operation of the second limit switch 523, it starts the piecing operation after the other signal is generated by the operation of the first limit switch 513.

The operational situation until the first limit switch 513 operates, will be hereinafter described with reference to FIGS. 44 and 45.

FIG. 44 is illustrative of the condition when the ring rail 502 is positioned at the lower limit of the chase. Thus, in FIG. 44, said projections 510 are respectively positioned at the bottom of the slots 509 and the cam 515 of the movable portion 511 is shifted downward from the actuator 514 of the first limit switch 513. When the ring rail 502 is elevated from the lower limit of the chase, said metal plate 503 of which plate member 505 is associated with the ring rail 502 is also effective to move vertically relative to the frame 501 for the piecing-up apparatus incident to elevation of the ring rail 502. At this time, the movable portion 511 being magnetically held to the metal plate 503 is also effective to move vertically therewith, and, shortly before the ring rail 502 arrives at the upper limit of the chase, projections 510 of the movable portion 511

respectively contact the top of the slots 509 thus stopping the movable portion 511 while the metal plate 503 continues to be raised by the ring rail 502. When this movable portion arrives at the top position, the cam 515 kicks the actuator 514 of the first limit switch 513 to generate therefrom an electrical signal. In the next place, the ring rail begins its downward travelling motion to descend to the lowermost position. At this time, the metal plate 503 also moves downwardly with the ring rail 502. Movable portion 511 moves downwardly with plate 503 so that the projections 510 are at the bottom of the slots 509 when one downward travelling motion of the ring rail 502 ends.

As can be now clearly understood, the upward travelling distance of the ring rail 502 is designed to be greater than the downward travelling distance so that the new chase is formed one after another by repeated travelling motion of the ring rail 502 incident to layers of yarn being wound onto the bobbin. The vertical path through which movable portion 511 travels is limited by slots 509 and is fixed relative to switch 513. It will be now understood that the movable portion 511 operates the first limit switch 513 at a fixed time with regard to the ring rail 502 arriving at the upper limit of the chase.

The supply of yarn is designed to be wound up onto the bobbin when the piecing-up apparatus, not shown, is operated to move by the signal generated by the first limit switch 513, for example, to supply the yarn to a traveller and when the ring rail arrives at the upper limit of the chase. In other words, the piecing-up apparatus is designed to enter in an auxiliary yarn joining process with a time delay equivalent to the quantity of time required for the ring rail 502 to arrive at the upper limit of the chase. This mechanical design provides that the auxiliary engages the bobbin at the position indicated with D in FIG. 43, that is, at the position on the bobbin wherein the extremely tapered line of the yarn layers is located. As previously described, the piecing-up apparatus is operated by the signal generated by the first limit switch 513 and then to join the auxiliary yarn thereto or to operate other processes essential to piecing, however, the time of the signal generated by the first limit switch 513 is adjusted by means of screws 508 which secure plate 506 in a proper position relative to the frame 501.

The mechanism is so designed that it is possible, in the event the bobbin is not filled at all, or filled with only a small amount of layers of the yarn, as shown by E in FIG. 43, the piecing operation may begin incident to the signal generation of the start thereof, while in the event the bobbin is filled with a certain amount of yarn, the auxiliary yarn must be joined at the position on the bobbin wherein the extremely tapered line of yarn layers is located. But, the piecing operation may be delayed until the initial signal effective to cause the piecing operation to begin is generated and the first limit switch 513 is operated, and then the piecing in the course of operation is done convenient to a rewinding process to be done later.

In the structure shown in FIGS. 44 and 45, the actuator 514 of the first limit switch 513 may be operated on by the cam 515 of the movable portion 511 and then may be left as it is during elevation of the ring rail 502 to the uppermost limit or permitted to descend later at a fixed distance after full elevation thereof, but this may bring the following inconvenience.

Since said metal plate 503 is so designed to cooperate during its vertical travelling motion with the ring rail 502, the metal plate 503 travels upward while the frame 501 for the piecing-up apparatus is travelling along the ring rail 502 to detect the proper position where to join the auxiliary yarn to the bobbin.

Subsequently, so long as the metal plate 503 cooperates with the ring rail 502, the first limit switch 513 unnecessarily generates a signal successively. This requires that the piecing-up apparatus arrive at a certain position relative to the bobbin to receive another signal representative of the start of the piecing operation and then the operation is accomplished by the signal generated by the first limit switch 513 after the apparatus stops at the proper position. In this case, when the piecing apparatus stops at the position where the operation is

to be performed and then generates the signal to cause the apparatus to perform its function, and when the ring rail 502 arrives near the upper limit of the chase at that time, the signal is generated by the limit switch 513 to cause the piecing operation to be performed since the first limit switch 513 has closed. Thus, if the piecing operation is performed with a timed delay after the signal is generated by the first limit switch 513, since the ring rail 502 is to descent at the beginning of the operation, the piecing position does not occur at the position indicated with *D* in FIG. 43, but at the inclined surface of the layers of yarn.

Consequently, it is desirable to apply an improved structure such as shown in FIG. 47. In this structure, a triangular member 517 effective to kick the actuator 514 of the first limit switch 513 is pivotably supported at 516 on the movable portion 511. The clockwise motion of the triangular member 517 is limited by engagement with fixed stop 518 carried by member 511 and member 517 therefore is effective to kick the actuator 514 during the course of the movable portion 511 travelling upward. On the other hand, in the course of the movable portion 511 travelling downward, as shown in FIG. 48, the triangular member 517 is swung upwardly about pivot 516 in a counterclockwise direction to bypass actuator 514. This mechanical design permits the actuator 514 of the first limit switch 513 to recover at the time the signal is generated incident to arrival of the ring rail 502 at the upper limit and also effective to cause the ring rail 502 to descent without operating the actuator 514. Only when the ring rail 502 arrives at a fixed position in the course of travelling upward, does the triangular member 517 kick the actuator 514 of the first limit switch 513 to generate the signal. Thus, this structure is effective to obviate any former inconvenience and effective to be used more practically.

As shown in said embodiment, the device is effective to determine a joining time when the ring rail arrives at the substantially upper limit thereof during its one travelling motion, and said device is also effective to protect the auxiliary yarn from being joined at the inclined surface of layers of yarn and effective as well to join said thread at the point on the bobbin wherein the extremely tapered line of layers of yarn is located. Thus, the yarn provided to be rewound from a full bobbin to a cheese does not get out of position from the bobbin with the pile coincident with said pile of the yarn becoming exposed to be unwound.

Furthermore, determination of the time to join the supplier thread is done through a drive motor effective to rotate a group of cams provided to drive therethrough the piecing-up apparatus shown in the second embodiment, said motor being driven by operation of the first limit switch 513. That is, since a time interval is fixed until every part of the apparatus begins to operate after the motor is driven, the supporter 506 may be preferably adjusted to its fitting position in a way that the first limit switch 513 is turned on during this time interval and earlier than the ring rail arriving at the upper limit of the chase.

Without depending upon the device shown in FIGS. 47 and 48, if the device is provided with a circuit wherein a pulse signal is generated at the moment the first limit switch 513 turned on, the piecing operation is performed by this pulse signal. Therefore, by applying this mechanism to the device shown in FIGS. 44 and 45, it may be more efficiently used without any inconvenience.

Also tensioning means or rubber means may be used instead of the magnets 512.

Especially, as shown in this embodiment, the spinning machine is provided with an apparatus effective to adjust the time to join the auxiliary yarn to the bobbin when the ring rail travelling motion is set at the substantially upper limit and also with a control device effective to restrict the time to join the yarn to the bobbin by means of the apparatus when said ring rail travels at the position extending beyond the normal position. When the auxiliary yarn is wound on an empty bobbin to lead the yarn or, when the bobbin is wound with a small

amount of the yarn while the ring rail travels at the lower position, said control device permits the piecing operation to start without any delay of time being required for the ring rail to arrive at the normal position. Thus, the embodiment offers a structure effective to provide an efficient piecing operation.

We claim:

1. In a method of piecing-up broken yarn ends by means of an auxiliary yarn on a spinning frame of the type including fiber drafting means, a twisting spindle, and a vertically reciprocable ring rail; which includes:

- a. bringing a length of auxiliary yarn to the vicinity of said spindle;
- b. effecting a threading engagement of said length of auxiliary yarn with a traveller on a ring surrounding said spindle and operatively engaging a free end of said auxiliary yarn with a bobbin on said spindle;
- c. braking said auxiliary yarn between its source and the spindle whereby it becomes taut and twisted between the braking position and the spindle;
- d. bringing an intermediate length of said twisted portion of auxiliary yarn into engagement with a portion of a roving extending from the drafting means;
- e. severing said auxiliary yarn between said braking position and said drafting means whereby said severed portion untwists and unites with said roving;

the improvement which comprises the additional steps of:

- f. accumulating a substantial length of auxiliary yarn within a narrow space under tension before it is supplied to the bobbin; and
- g. thereafter rapidly supplying at last a portion of said substantial length to the bobbin in untensioned condition.

2. The method of piecing-up broken yarn ends as claimed in claim 1, wherein, in step (f), the auxiliary yarn is supplied to the narrow space by an air jet.

3. The method of piecing-up broken yarns ends as claimed in claim 1, wherein the auxiliary yarn is engaged with the bobbin near the top level of reciprocating movement of the ring rail while yarn is being wound in coplike form.

4. In a piecing-up apparatus for a spinning frame of the type including fiber drafting means, a twisting spindle, and a vertically reciprocable ring rail; which includes:

- a source of auxiliary yarn, means effecting a threading engagement of said auxiliary yarn with a traveller on a ring surrounding said spindle and thereafter operatively engaging a free end of said auxiliary yarn with a bobbin on said spindle; means for braking said auxiliary yarn between its source and said spindle whereby said auxiliary yarn becomes taut and twisted between the braking means and the spindle; means for moving an intermediate length of the twisted portion of auxiliary yarn into engagement with a portion of a roving extending from the drafting means; and means for severing said auxiliary yarn between said braking means and said drafting means whereby said severed portion untwists and becomes united with said roving;

the improvement comprising: means forming a narrow passage; means for accumulating a relatively long length of auxiliary yarn under tension within said narrow passage prior to engagement of the free end with the bobbin; means for moving a portion of said accumulated length of auxiliary yarn laterally of said narrow passage, and means for releasably holding said portion while under tension and while said free end is being operatively engaged with the bobbin, the subsequent winding of said yarn on said bobbin action to pull the yarn from said releasable holding means thereby suddenly reducing the tension on said portion and permitting it to be rapidly wound on said bobbin without breakage.

5. In a piecing-up apparatus as claimed in claim 4, wherein said means for accumulating auxiliary yarn comprises split pulley means.

6. In a piecing-up apparatus as claimed in claim 5, wherein said split pulley means serves also as said braking means.

7. In a piecing-up apparatus as claimed in claim 5, wherein said split pulley surrounds the upper end of said narrow passage, and wherein the means for accumulating a length of auxiliary yarn also comprises air jetting means so located that air is jetted into said narrow passage and acts to draw yarn from said split pulley into said passage when the two portions of said split pulley are separated.

8. In a piecing-up apparatus as claimed in claim 7, wherein said split pulley means includes an auxiliary yarn winding tapered portion which cooperates with said air jetting means whereby yarn accumulated on said tapered portion is drawn into said narrow passage when the two portions of said split pulley are separated.

9. In a piecing-up apparatus as claimed in claim 4, wherein said apparatus includes a first switch means which determines the time of starting the piecing-up operation, said first switch means comprising a metal plate which reciprocates vertically with the ring rail, a member secured to said metal plate by means normally compelling said member and plate to move as a unit but permitting relative vertical movement therebetween when said member is stopped in its upward movement, a switch fixed on the piecing apparatus, and switch-actuating means on said member, the vertical path of movement of said member being fixed relative to said switch, and the switch

being actuated by said switch-actuating means at the upper limit of said path and near the top level of the ring reciprocating movement.

10. In a piecing-up apparatus as claimed in claim 9, wherein said apparatus includes a second switch means, said first switch means being effective only after said second switch means detects a predetermined level of the ring rail relative to the spindle, said predetermined level being a top level of said reciprocating movement of the ring rail at which yarn begins to be wound into regular coplike form.

11. In a piecing-up apparatus as claimed in claim 4, wherein the drafting means includes front drafting rolls along and between which the roving traverses during the drafting operation, and wherein said means for moving a twisted portion of auxiliary yarn toward the roving includes a guide means having a guiding portion for the auxiliary yarn, said guide means having at its outer end converging edges for engaging and spreading said roving portion and a narrow slit connecting said edges and said guiding portion for said auxiliary yarn, said guide means being resiliently mounted for yielding lateral movement in the direction of traverse of the roving along the rolls of the drafting means.
